BRUSH ASSEMBLY

William C. Van Cleave, Jr., Baltimore, and Joseph V. Mertes, Catonsville, Md., assignors to Pittsburgh Plate Glass Company

Application December 23, 1952, Serial No. 327,608

8 Claims. (Cl. 15—202)

This invention relates to a brush involving a bristle portion comprising a bristle body detachably secured in a socket, or ferrule upon a handle, and it has particular relation to a brush of the foregoing type adapted for application of paints and similar coating materials to surfaces.

An object of the invention is to provide a simple inexpensive brush strip which can be detachably secured in a socket upon a handle to provide a brush.

A second object is to provide a brush bristle strip structure of the foregoing type, a plurality of units of which are adapted to provide a highly efficient brush.

A third object is to provide a simple and efficient socket structure for securing brush strips to a handle.

A fourth object is to provide a simple and efficient clamping structure for securing the brush strip in a socket.

These and other objects will be apparent from consideration of the following specification and drawings. It is to be understood that no particular effort has been made to correlate the numbers of the object with their relative importance. It will further be understood that all of the foregoing objects need not necessarily be attained simultaneously.

For a better understanding of the invention reference may now be made to the accompanying drawings in which like numerals refer to like parts throughout and in which:

Fig. 1 is a view partially in elevation and partially in section of a brush embodying the principles of the invention.

Figure 2 is a sectional view taken substantially upon the line II—II of Figure 1.

Figure 3 is a sectional view taken substantially upon the line III—III of Figure 2 with the bristles omitted.

Figure 4 is an end elevational view of a bristle socket such as is shown in Figures 1 and 2.

Figure 5 is a side elevational view of a screw device employed for securing a bristle socket to a handle in the embodiment of the invention shown in Figure 1.

Figure 6 is a side elevational view of the screw device illustrated in Figure 5.

Figure 7 is a side elevational view of a slightly modified form of screw device.

Figure 8 is an elevational view of a bristle appropriate for use in the practice of the invention. It is to be understood that in this figure no particular effort has been made to maintain correct relative proportions between the thickness and the length of the bristle.

Figure 9 is a side elevational view of a second brush structure embodying the invention.

Figure 10 is a view partially in elevation and partially in section as taken from the side of the structure shown in Figure 9.

Figure 11 is a sectional view taken substantially upon the line XI—XI of Figure 10 with the bristles omitted.

Figure 12 is a sectional view taken substantially at the midsection of a bristle strip as employed in practice of the invention.

2

Figure 13 is an end elevational view of the bristle strip shown in section in Figure 12.

A conventional brush structure comprises a handle element having a flared head and a bristle body secured thereto, usually by a band of metal known as a ferrule which is wrapped about the head of the handle and the brush bristle body in such manner as to provide a socket for the bristle. Usually the ferrule is secured to the handle by means of nails and conventionally, the bristles are secured in the socket by a matrix of plastic such as rubber or the like.

The manufacture of such brush requires a great many hand operations by skilled workmen and also considerable amounts of relatively expensive materials are required. The mass of bristles in the brushes is relatively thick and difficult if not impossible adequately to clean. The brushes when worn out, or when they become fouled by accumulation of dried paints, cannot readily be restored to working condition and therefore, must be discarded in their entirety, at considerable expense.

This invention comprises, as one feature, the formation of brush bristle body of a plurality of relatively thin bristle strips which are formed simply of narrow, but appropriately shaped, channels in each of which the bights of double-ended bristles are looped about a core running longitudinally of the channel and the bristles are locked in position in the channel by crimping, or inwardly bending the side walls of the channels. The use of a bonding agent for securing the bristles in such channels is not required. These bristle strips can, if desired, be very cheaply formed by mechanical means, even as a continuous band or bar which is subsequently cut into sections of appropriate length.

The invention further includes an inexpensive socket construction designed releasably to clamp the particular bristle sections so that they can be removed for cleaning, or when they are no longer serviceable, they can be readily and inexpensively replaced by new sections or strips.

The invention still further includes appropriately longitudinally curving or bending the channels of the brush sections or strips and so shaping the transverse sections thereof that they will coact with the sockets in properly disposing the tips of the bristles so that the tips of one section are pressed against the tips of a second section whereby, in effect, to form a unitary brush bristle body.

In the embodiment of the invention illustrated in Figures 1 through 7 inclusive, a detachable handle 20, of wood, plastic, or the like is provided at its upper end constituting a brush holding portion with an internally threaded portion, which, optionally may be formed in the material of the handle or in thimble 21 embedded in the handle. The other end of the handle constitutes a gripping portion. A cup-like socket or ferrule 22 is disposed upon the handle and includes a web-like bottom 23 having a central opening 23A for a securing device (to be described later) and being provided with outwardly bowed side walls 24 and 25, as well as end walls 26 and 27. Preferably, the socket is formed from metal such as iron or aluminum by a simple stamping operation upon a blank from a sheet of reasonably heavy gage. This operation can be performed mechanically and very inexpensively.

The brush bristle strips S as shown in Figure 2 of the drawings, are formed of channel sections or segments 29, also of metal, e. g. aluminum, or other suitable material. They include webs 30, having inside walls 31 and outer side walls 32. Bristles 33 for use in the sections may be of uniform diameter at all points in their length, but preferably, they are tapered. Also, they preferably are double-ended and in the channels are bent approximately to U shape as indicated in Figure 8. They include bight

portions B, which are looped about filamentary cores or rods 34 so that the tip portions project upwardly to provide the brush bristle structure. These bristles may conveniently be formed of a synthetic plastic such as cellulose acetate, nylon, or the like, by extruding a solution, or a melt of the plastic through spinneret openings. The tapering effects may be obtained by application of regularly pulsating pressures in the spinning operation, or by varying the speed of the take-up rollers as the filaments are spun. Long filaments of varying diameter, thus spun out may be cut through the constricted portions to provide the double-ended bristles, which, in use, are doubled about core 34 so that each, in effect, provides a pair of bristles. The spinning of such bristles and the subsequent formation of bristle strips therefrom, within itself, does not constitute a feature of this invention except insofar as they are combined with certain other features herein disclosed. Elaboration upon the techniques of spinning the bristles and forming the brush strips, accordingly, is not deemed to be necessary.

It is sufficient to state, as previously intimated, that the strips are usually formed on a machine as a long, even substantially continuous strip from a roll or ribbon of metal which is shaped to form a channel to receive the bristles and their retaining core. The channel and core are then cut into sections of proper length for a brush. To prevent longitudinal displacement or loss of the bristles, the ends of the side walls may further be crimped inwardly as indicated at C in Fig. 12 until the corners meet or nearly meet. The crimping may be done prior to, simultaneously with, or subsequent to the cutting operation.

The bristles may also be secured in the channels by cohering them. A most convenient method of attaining this result involves performing the cutting operation upon the channel by means of a friction disc or cutter, the peripheral speed of which is adjusted to produce a large amount of frictional heat. This speed, naturally will vary with the cutting characteristics of the disc, the degree of ventilation in the cutting zone, the degree of hardness of the metal etc. Best speed is determined experimentally for each set of conditions. The frictional heat may be relied upon to partially fuse the bright portions of bristles contiguous to the cutting zone, thus cohering the brights at such points into a solid mass, whereby to assure their retention in the channel. Enough heat is generated to fuse the brights of the bristles without charring them. The metal of the channel at the cut may even be sufficiently heated to produce a weld between the sides of the channels across the ends. However the temperature is attained for such short time that no substantial damage is done to the bristles contiguous to the channel.

During or subsequent to the cutting and crimping operations, the channel sections may also be slightly bent, for example as by transverse pressure at their mid points. The bend may be continuous as shown, from end to end, or it may be upon a relatively short radius at and near the mid point, with the portions beyond, remaining nearly straight. Preferably enough bend is imparted as almost to bring the ends of the channels together when the brush is assembled.

As will be observed in Figure 2 of the drawings the side walls 24 and 25 of the socket 22 are substantially inwardly inclined with respect to each other to impart to the socket a trapezoidal section. It will also be observed that the outer side walls 32 of the bristle strips are correspondingly inwardly inclined so that when the strips are correctly positioned, the angles of the side walls of the socket and of the channels substantially coincide. The inner side walls 31 of the channels, preferably, are most nearly vertically disposed when the channels are seated in the socket. It will be understood from the drawings that before the channels are inserted in the socket, outer

edge portions of the channels, at the mid-portions are slightly lower than the corresponding edge portions at the tips. As shown in Fig. 12, an apex P constituting a fulcrum is thus provided and the channels are tipped slightly inwardly thereabout, so that the tip portions of the bristles of a strip or section, along the inner face, are pressed against the corresponding bristles of the contiguous section. Since the inner edges of the channels are also rounded as indicated at R, it will be evident that even further tipping effects can sometimes be attained by rocking the channels on their rounded edges by the clamping screw to be described below.

For purposes of securing the channels of the strips in the sockets in proper position, a screw device such as 35 is provided. This device may conveniently be stamped or cut from a small square of sheet metal having, for example, the shape illustrated in Figure 5. The broken lines indicate portions that have been sheared away from the original blank. The device includes a stem portion 36 extending through opening 23A in socket 22, and a head portion 37 that gives the device a T shape. Normally, the thickness of the sheet metal from which the screw device is stamped can be less than the diameter of the sleeve 21, as is clearly shown in Figure 2 of the drawings. This facilitates shearing out and shaping the device. The edge portions of the stem are provided with serrations 38 which are formed to function as threads in combination with the threads of the sleeve or thimble 21. Preferably, the upper edge of the head portion 37 is laterally indented to provide the sinuations 39 shown in Figure 3. The lower edge of the head portion 37 need not be sinuated. An over-all wedge effect is thus imparted to the head, even though the latter is formed from sheet material of uniform thickness. When stem 36 is inserted in opening 23A of socket 22 and is threaded into the sleeve 21, the head portion 37 is drawn down between the channels of the strip elements, thus first forcing them into engagement with the side walls 24 and 25 of the socket. In the device shown in Figures 2 and 6, in order to insure that the inner edges of the channels are held down in such manner as to effect a tilting action to bring the tip portions of the bristles together between the respective sections, notches may be formed in the peaks of the sinuations 39, slightly below the upper edge of the head element 37. Slight ledges, as indicated at 41 are thus formed and are adapted to hook over the upper edges of the inner sides of the channels, when stem 37 is screwed into thimble 31, whereby positively to clamp the inner edges of the channels down when the screw device 35 is tightened. The channels rock inwardly first upon the apexes P, and then, if the side walls 32 are not firmly in contact with the side walls of socket 22, they may tilt even further on rounded edges R, to press the tip portions of the bristles of one section toward those of the other.

Often the ledges 41 are not required to secure adequate inward tilting of the channels if the socket and the channels are well formed. A device free of such ledges is shown in Figs. 3 and 7. The wedging effect of the T head 37 may force the outer edges under side walls 24-25 of the socket sufficiently to produce adequate tilting. Naturally, the more sharply the inclination of the side walls 24-25 with respect to channel walls 32, the greater will be the degree of tilt. Usually the angle of the walls 24-25 of the socket with respect to the vertical will be greater than will be the corresponding angle of side walls 32 of the channels. In Figures 3 and 7, the screw device is shown as being devoid of ledges 41. The numbers in this embodiment of screw device are distinguished from Figure 6 by the subscript A.

In some instances it may also be desirable to provide the web portion 23 with a slight downward convexity in its cross section. Such section assists in tilting the bristle strip sections inwardly.

In view of the bow in the channels, it will be apparent that the tip portions swing slightly downward when the channels are inwardly tipped with peak P as a fulcrum. The downward bending of the ends of the channel elements is best illustrated in an exaggerated degree in Figure 12 which shows a section taken approximately at the mid point of the channel. The slight downward drooping of the ends of the socket 22 permits the curved or bent channel so to tilt, while at the same time it seats firmly at its ends and mid point against web 23.

In the assembly of a brush from the preceding elements, the stem portion 36 of a screw device 35 or 35A is inserted through the hole or opening 23A in the web portion 23 of the socket 22 and is threaded into the screw threaded portion or thimble 21 of the handle 20 a short distance. The channels of the bristle strips may then be inserted in the socket 22, on each side of the head 37 or 37A of the screw device and the bristle strips may be manually pressed toward each other. The handle 20 is then turned on the stem 36 or 36A of the screw in order to tighten up the head. In the form shown in Figures 2 and 7, the ledges or hook portions 41 engage over the upper edges of the channels 31 as shown in Fig. 2. The channels are thus securely wedged apart so that the outer walls 32 thereof contact the walls of the socket. At the same time, if screw device 35 has ledges 41, they press downwardly, so that the channels are locked at their inner edges. In any event the channels are tipped inwardly slightly in order to insure that the inner bristles of one bristle section are pressed at their tip portions against the corresponding tip portions of the other bristle section.

The construction as shown in Figures 9 and 10 is quite similar to that shown and described in connection with Figures 1, 2, 3, 4, 5, 6, 7, and 12 except that a somewhat modified form of screw device is employed for locking the channels of the brush bristle strips in the socket and for holding the socket on the handle. In the modified construction, the handle indicated at 50 may be substantially similar to that shown in Figure 1 and may include an internally threaded sleeve or thimble 51 into which is threaded a headless stud screw or bolt 52 extended through opening 53 in the bottom of a socket 54. Bolt 52 has a nut 55, threaded upon the upper end thereof and functioning as a head for locking the channels 56 of the brush bristle strips in the socket 54. Nut 55 may have vertical sides, or the sides may be beveled to fit the sides of the brush bristle strips. The extremities of the socket 54 and channels 56 are bent downwardly in the manner described in connection with the preceding embodiment of the invention. The socket also has upwardly converging sidewalls 57 and 58. The brush bristle strips comprising channels 56 are preferably bowed inwardly at their ends in the manner above described and the bristles in the channels are also of the double-ended type already described and are locked in the channels by the cores 63.

In the assembly of this construction, the screw 52 preferably is started in the sleeve 51, the socket 54 is disposed upon the screw and the nut 55 is started upon the upper extremity of the screw. The channels 56 of the brush bristle strips may be disposed in the socket upon opposite sides of the nut 55 after which the handle 50 is rotated to tighten up the screw and to draw the nut 53 down between the channels. If the nut has vertical sides, it will be observed that at its lower corners, it contacts the channels slightly to bite into the latter. This action assists in drawing the inner edges of the channels downwardly thus insuring that the channels are properly seated in the socket 59 and that the bristles along the inner faces of the bristle strips, are pressed against each other to provide a unitary brush body in which there is no space between the two sections of bristles at the tips thereof. If the nut has sloping 75

sides, a wedging effect is produced which usually is sufficient to secure the bristle strip channels in desired position.

It will be observed that in event that it is desired to remove the bristle strips from either of the previously described constructions, the handles are merely rotated upon the screw devices until sufficient space is afforded between the nut 55 or the head 37 and the sidewalls of the socket element, to permit the withdrawal of the channels of the bristle strips. These individual strips may then be washed, the washing operation being considerably facilitated because each strip is only half the thickness of the assembled brush. If for any reason it is desired to replace the bristle strips, new strips can be substituted thus restoring the brush substantially to its original usefulness. The bristle strips are relatively inexpensive to obtain since they can be manufactured substantially without application of manual labor.

The forms of the invention herein described are to be considered as being by way of illustration. It will be apparent to those skilled in the art that numerous modifications may be made therein without departure from the spirit of the invention or the scope of the appended claims.

We claim:

1. A brush bristle strip comprising a channel having side walls joined by a web and double-ended U-shaped bristles having their bights disposed about a filamentary core in the channel, the side walls being inwardly crimped to secure the bristles in the channel, the mid-portion of the channel being laterally bent, the portion of the web contiguous to the end of the channel being substantially lower on the convex side than on the concave side, whereby to provide a fulcrum for tipping the channel.

2. A brush assembly comprising a pair of mating channels having bristles secured therein and being disposed in a socket having side walls and an intermediate web interconnecting the side walls, means of securing the socket to the handle comprising a screw element extending through the web of the socket and into the contiguous end of the handle, a head member upon the screw element having overhanging portions adapted to hook over the edges of the inner walls of the channels to clamp the webs thereof against the web portion of the socket and to tip the channels toward each other.

3. A brush assembly comprising a socket member secured upon the upper end of a handle, said socket member being transversely elongated and having the extremities thereof downwardly bent, a pair of brush bristle strips comprising channels laterally bent and having the concave sides thereof facing each other whereby the tip portions are in contiguity with respect to each other and a screw element threaded into the socket and having portions engaging the top edges of the side walls of the channels whereby to keep the channels inclined slightly toward each other in the socket.

4. A brush assembly comprising a handle having a socket for bristles, bristle strips comprising a pair of curved channel sections disposed with their concave sides facing each other and each having a pair of side walls joined by intermediate webs, bristles secured in the channel sections and means associated with the socket and the channel sections for maintaining the channel sections in mutually inwardly inclined position with respect to each other, whereby the tips of the bristles upon the inner side of a bristle strip are pressed against the tips of the bristles on the inner side of the contiguous strip to form a continuous brushing surface.

5. A brush comprising a handle having a brush holding end and a gripping end, an elongated socket of sheet metal secured upon the first mentioned end and being shaped to provide inwardly inclined side walls and an interconnecting web, said side walls being convexly outwardly bowed at their mid portions, a pair of spaced channel sections disposed in the socket and having their

sides convergent away from the web and being outwardly bowed to correspond to the outward bowing of the side walls of the socket, the tips of the socket being bent toward the second mentioned end of the handle, the channel sections being tipped toward each other and the tip channel portions of the bristles on the inner side of one channel section being pressed against the corresponding portions of the bristles on the inner side of the other channel section and means locking the channel sections in position in the socket.

6. A brush bristle strip as defined in claim 5 in which the bristles are formed of a thermoplastic plastic material and the butt portions of the bristles, at the tips of the channels, are fused together as a coherent mass securing the bristles against longitudinal displacement in the channel.

7. A brush comprising a handle having a brush end and a gripping end, an elongated socket of sheet metal disposed transversely upon the first mentioned end and being shaped to provide inwardly inclined side walls and an interconnecting web, a pair of spaced channel sections disposed in the socket and having side walls inclined toward each other, but away from the web, bristles having their butt portions locked in the channels, and screw means for securing the socket to the handle, comprising 25 a T-shaped element of sheet metal, the stem of the T constituting the stem of the screw, the cross of the T being of substantially uniform thickness and the upper edge thereof being sinuously laterally bent to impart a wedge shape to the cross and adapting said device for 30 wedging the channel sections against the side walls of

- 5 the socket in inwardly inclined position and the stem extending through the web and being threaded into the handle to secure the handle and socket together.
8. A brush comprising a handle having a brush end and a gripping end, an elongated socket of sheet metal secured transversely upon the first mentioned end of the handle and being shaped to provide inwardly inclined side walls and an interconnecting web, said side walls being convexly outwardly bowed, a pair of spaced channel sections disposed in the socket and having their sides convergent away from the web and being outwardly bowed to correspond to the outward bowing of the side walls of the socket, the ends of the socket being bent backwardly toward the gripping end of the handle and a screw comprising a wedge-like head portion wedging the sections against the side walls of the sockets in inwardly inclined position with the tips thereof drooped toward the second mentioned end of the handle, the stem of said screw means extending through the web and being threaded into the first mentioned end of the handle to secure the handle and socket together.
